UNITED STATES PATENT OFFICE.

WILLIAM F. LINDSEY AND WILLIAM H. FINLEY, OF SAMOTH, ILLINOIS

FENCE-BUILDING APPARATUS.

SPECIFICATION forming part of Letters Patent No. 772,810, dated October 18, 1904.

Application filed April 24, 1903. Serial No. 154,068. (No model.)

To all whom it may concern:

Be it known that we, WILLIAM F. LINDSEY and WILLIAM H. FINLEY, citizens of the United States, residing at Samoth, in the county of Massac, State of Illinois, have invented certain new and useful Improvements in Fence-Building Apparatus; and we do hereby declare the following to be a full, clear, and exact description of the invention, such as will enable others skilled in the art to which it appertains to make and use the same.

This invention relates to apparatus for building fences, and has for its object to combine in a single device a mechanism which may be used in building fences of two kinds—viz., the style of fence in which strand-wires are arranged in pairs and palings or slats are disposed between the wires, the wires between the palings being twisted to cause the wires to closely hug the palings and hold them in place, and the style which consists of tightly-stretched wires secured to posts—the device providing means for attaching thereto the pairs of wires of the first form and for stretching the strand-wires of the second form and being so constructed that a single upright or support suffices for both the wire stretching and fastening means.

In the drawings forming a portion of this specification, and in which like numerals of reference indicate similar parts in the several views, Figure 1 is a side elevation of a panel of fence in course of construction, showing the present apparatus in position at one end thereof. Fig. 2 is a section on line 2 2 of Fig. 1. Fig. 3 is a section on line 3 3 of Fig. 1.

Referring now to the drawings, there is shown an upright 5, having vertically-spaced slots 15 therethrough, in which are secured the ends 6 of laterally-projecting arms 16 and 17 by means of pins 18 passed through alining perforations 18', formed in the post at the sides of the slots. The arms 16 and 17 are each provided with a series of perforations, through which are passed pins 8 for purposes to be presently described.

Between the slots 15 are a pair of slots 9 and 10, between which is the central portion 11 of the upright. In the slots 9 and 10,

against the upper and lower faces, respectively, of the central portion 11, are disposed ends 12 and 13 of a yoke 23, having shoulders 31, which bear against the rearward face 11' of the portion 11. The slot 10 receives 55 slidably therein a rack-bar 20, having a link 22 at its forward end for the attachment of a wire 28, and this rack-bar 20 is engaged by a pawl 29, pivoted within the slot 10, so as to allow of rearward movement of the bar. 60 This pawl 29 has a finger 29' extending outwardly of the slot 10, by means of which the pawl may be disengaged from the rack-bar.

To move the rack-bar within the slot 10, there is pivoted in the yoke 23 a lever 24, 65 which has pivoted at its lower end a pawl 27' for engagement of the rack-teeth and which may be moved out of engagement with the teeth by means of a rod 26 and hand-lever 27, as shown. 70

In constructing a fence with the present apparatus the posts are planted in the ground in the customary manner and the upright 5 is planted in the ground in a line with the posts. A brace 9', which is pivoted to the 75 upright above the arm 16, is engaged with the last post to prevent tilting of the upright, and strand-wires 28' are attached in pairs adjacent to the upper and lower ends of the first post. The free ends of the wires are now 80 engaged with the pins 8 of the arms 16 and 17, around which they are wound alternately, each pair of wires being engaged with the ends of the pins at opposite sides of the arms. Panels or pickets are now engaged between 85 the wires of each pair, and the wires are then given a single twist, after which another picket is engaged in a similar manner, and the twisting operation is repeated. In attaching barb or other strand wires to the 90 faces of the pickets or in building a fence wherein pickets are not used a wire 28 is attached to the rack-bar 20 through the medium of the link 22, as described, and the bar 20 is then moved rearwardly through the medium of the lever 24 to stretch the wire 28, which may be then fastened to the posts and pickets in any desired manner. 95

As shown, the slots 15 are somewhat larger than the ends of the arms 16 and 17, the ob- 100

ject of this being to permit of removal of the arms therefrom to allow of vertical adjustment of the wire-stretching mechanism, the solid portions of the uprights between the 5 slots 9, 10, and 15 being substantially the same in width to receive the bracket 23.

It will thus be seen that there is provided a fence-building machine which may be used for constructing either kind of fence as mentioned above and which may be used for constructing a combination-fence. This result is obtained by the arrangement of the post, which makes possible the use of the wire stretching and attaching mechanism in connection therewith.

The slots 15 and the intervening solid portions are of the same size, and there is thus provided a post which is so constructed that the wire-stretching mechanism may be moved 20 vertically thereof to permit of attachment of wires at different points vertically of the fence.

In practice modifications of the specific construction may be made and any suitable material may be used without departing from the 25 spirit of the invention.

What is claimed is—

1. In a fence-building apparatus, the combination with a post having openings therethrough and intervening solid portions, of 30 wire - stretching mechanism comprising a bracket including spaced legs engaged with the solid portions, a hand - lever pivoted in the bracket, a dog carried by the hand-lever, a ratchet-bar adapted for engagement with the 35 opening below the bracket and adapted for at-

tachment of a wire to one of its ends, said dog being adapted to engage the teeth of the rack-bar to move it through the opening to place tension upon the wire, and a dog pivoted in the opening and lying in engagement with the 40 teeth of the rack-bar to hold it against movement under tension of the wire.

2. A wire-stretcher comprising a post having openings therethrough and intervening solid portions, said openings having alining 45 perforations in the sides thereof, a bracket including spaced legs engaged with one of the solid portions, a hand-lever pivoted in the bracket, a dog carried by the hand-lever, a ratchet-bar disposed in the opening below 50 the bracket and adapted for the attachment of a wire to one of its ends, said dog being adapted to engage the teeth of the bar and to move it in one direction through the opening to place the wire under tension, a pin disposed 55 in the alining perforations in the sides of the opening, and a pawl pivoted upon the pin and lying in engagement with the teeth of the ratchet-bar to hold it against movement under tension of the wire, said wire-stretching 60 mechanism being adapted for engagement with the remaining openings and intervening solid portions interchangeably.

In testimony whereof we affix our signatures in presence of two witnesses.

WILLIAM F. LINDSEY.
WILLIAM H. FINLEY.
